UNITED STATES PATENT OFFICE.

THOMAS A. CASEY, OF NEW YORK, N. Y., ASSIGNOR TO FRANCIS W. JONES,
OF SAME PLACE.

PNEUMATIC-DESPATCH TUBE.

SPECIFICATION forming part of Letters Patent No. 592,765, dated November 2, 1897.

Application filed January 20, 1897. Serial No. 619,905. (No model.)

To all whom it may concern.

Be it known that I, THOMAS A. CASEY, a citizen of the United States, and a resident of New York, in the county and State of New York, have made certain new and useful Improvements in Pneumatic-Despatch Tubes, of which the following is a specification.

My invention is an improvement in pneumatic despatch or carrier tubes.

10 The object of my invention is to automatically cut off the propulsive current of air just before the carrier has arrived at its destination without interposing any mechanical obstruction in the path of the carrier, where-
15 by I save wear upon and injury to such carrier. I provide an opening in the wall of the tube near the destined point or station. Surrounding this opening upon the exterior of the tube is a chamber, which may be cylind-
20 drical. In the chamber or cylinder is a valve having a piston or similar mechanical attachment. A spring or similar retracting device tends to force the valve into position to close the aperture or opening in the tube. In prox-
25 imity to this valve there are two electrical contact-points, one of which is movable and has a spring tending to draw it into engagement with its companion contact. At the station starting or sending the carrier or at
30 the point where is located the means for applying the propulsive air-current, or both, there is an electromagnet to control such means of turning on and off or applying the air. An electric circuit includes this magnet
35 and the described contact-points.

The carrier in its passage forces air against the valve, which is thus caused to release the movable circuit-closing point or contact to close the circuit, energize the magnet, and cut
40 off the propulsive air-current.

The accompanying drawing illustrates my invention.

P is a well-known arrangement of pneumatic tube.
45 R is a reservoir of any suitable compressed gas, preferably atmospheric air. It is supplied through means of the engine E and cylinder and pump c, of any well-known construction.

S is a supply-pipe connecting the tube with 50 reservoir R. There is a valve V controlling the access of compressed air. The valve is operated by a lever L, which carries the door g to close the opening through which the carrier is introduced. A weight w is placed on 55 lever L, sufficiently heavy to operate the valve V by gravity.

I have shown two stations, X and Y. At X there is an electromagnet M, having an armature a, carrying a bell-hammer. There 60 is a bell or signaling device B. The armature-lever a is provided with a hook or catch n in position to engage with lever L when the door g is closed and the valve V open. At station Y there is a hole or aperture o in the 65 side wall of the tube, surrounding which is a chamber or cylinder E. There is a valve d normally held against the hole o by means of the spring s, said valve having a rod r fixed to it and extending outside of the box or inclosure E. This rod r has a hook or catch m upon its outer end, which holds the movable contact l away from the fixed contact or stop p. The movable contact l is pivoted at 70 13, and a retracting-spring 14, acting contrary to 75 the spring s, tends to draw said contact l toward the fixed contact p. From the contact p a conductor extends to the terminal of the magnet M at the starting-station X, and from the movable contact l a conductor 2 extends 80 to the second terminal of said magnet. There is a battery MB located in said circuit, and when the contacts l p are closed the magnet M is energized.

The operation of the apparatus is as follows: Referring to station X, when the carrier has been introduced for transmission to station Y the door g is lifted by hand and closed, where it is engaged and held in position by the catch n on the armature-lever a, 85 valve V being simultaneously opened. As the carrier passes station Y the air in the tube forces the valve d away from opening o, releasing lever l, which contacts with stop p, current passing via wires 1 and 2 to magnet M, which is energized and attracts its armature a, releasing the valve-lever L. Door g is opened by gravity, valve V closed, and

at the same time a signal is sounded whereby the arrival of the carrier at the distant station is made known.

What I claim, and desire to secure by Letters Patent, is—

1. The combination of a pneumatic tube, an opening in the wall of the tube at or near one station, an exterior chamber inclosing said opening, a valve in said chamber, a spring holding said valve in position to close said opening, a contact-point, a movable contact-point, a spring tending to draw the movable contact into engagement with the first-named contact, a mechanical connection between the valve and movable contact, means for cutting off the propulsive air-current at a separated or distant point, an electromagnet controlling such means, and an electric circuit including said contact-points and magnet, substantially as described.
2. The combination of a pneumatic tube,

an opening in the wall of the tube at or near one station, an exterior chamber inclosing said opening, a valve in said chamber, contact-points controlled by said valve, means for controlling the propulsive air-current, an electromagnet controlling such means, and an electric circuit including said contact-points and magnet, substantially as described.

3. The combination of a pneumatic tube, an opening in the wall of the tube at or near one station, an exterior chamber inclosing said opening, a valve in said chamber, contact-points controlled by said valve, a device for controlling an entrance to said tube, an electromagnet operating said device and an electric circuit including said contact-points and magnet, substantially as described.

THOMAS A. CASEY.
